US0D1037328S

(12) **United States Design Patent** (10) **Patent No.:** **US D1,037,328 S**
(45) **Date of Patent:** **** Jul. 30, 2024**

(54) **AUTO SMART HEAT PRESS**

(71) Applicant: **Ying Zhou**, Hubei (CN)

(72) Inventor: **Ying Zhou**, Hubei (CN)

(**) Term: **15 Years**

(21) Appl. No.: **29/938,303**

(22) Filed: **Apr. 19, 2024**

(51) **LOC (14) Cl.** **15-10**

(52) **U.S. Cl.**

USPC **D15/146**

(57) **CLAIM**

The ornamental design for a auto smart heat press, as shown and described.

DESCRIPTION

FIG. 1 is a perspective view of a auto smart heat press showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the auto smart heat press and form no part of the claimed design.

1 Claim, 8 Drawing Sheets
